Joseph O. Pollack, Chicago, Ill.

Application September 4, 1934, Serial No. 53,192

Term of patent 7 years

To all whom it may concern:

Be it known that I, Joseph O. Pollack, a citizen of the United States, residing at Chicago, in the county of Cook and State of Illinois, have invented a new, original, and ornamental Design for a Combination Pin and Double Safety Guard, of which the following is a specification, reference being had to the accompanying drawing, forming a part thereof.

Fig. 1 is a front elevation of the combination pin and double safety guard; and

Fig. 2 is a side elevation of the same.

I claim:

The ornamental design for a combination pin and double safety guard, as shown.

JOSEPH O. POLLACK.
